UNITED STATES PATENT OFFICE.

CARL FRIEDRICH WURMBACH, OF MÜSEN, GERMANY.

DISINTEGRATING-MACHINE FOR GLUE PIECES.

SPECIFICATION forming part of Letters Patent No. 609,489, dated August 23, 1898.

Application filed April 19, 1895. Renewed March 14, 1898. Serial No. 673,865. (No model.)

To all whom it may concern:

Be it known that I, CARL FRIEDRICH WURMBACH, manufacturer, of Müsen, near Dahlbrück, in the Kingdom of Prussia, German Empire, have invented new and useful Improvements in Disintegrating-Machines for Glue Pieces and the Like, (for which I have obtained patents in Germany, No. 81,690, dated June 15, 1895; in Austria, No. 45/212, 10 dated January 17, 1895; in France, No. 242,894, dated March 5, 1895, and in Great Britain, No. 22,634, dated November 22, 1894,) of which the following is a specification.

My invention relates to improvements in 15 disintegrating-machines for glue pieces and the like, and has for its object a disintegrating machine or devil for the glue pieces which constitute the raw material for the manufacture of size. This raw material consists of 20 skin-parings, refuse, or waste, but not that proceeding from the tanned parts of the said skin, which parings, &c., when wet are very tender and elastic and of varying thicknesses.

In order to obtain as good and as uniform 25 a product as possible, the glue pieces for the size must be disintegrated or deviled before being boiled in their wet state; and this operation forms the object of this invention.

This invention has thus for its object the production of a raw material of the greatest possible uniformity, and hence having the form 30 of fibers.

The great advantage offered by such a disintegrating-machine is not only to allow the 35 manufacture of size from raw material to take place in a quicker, safer, and more productive manner, but also to produce a cleaner and more valuable size.

According to the processes hitherto used, 40 whereby uneven and dissimilar glue pieces and the like constituted the raw material treated, it was not possible to obtain a regular and uniform treatment, and the resulting product was inferior in quality and in value. 45 Great difficulties have always been encountered in the disintegration of glue pieces, and all endeavors made in this direction have hitherto yielded no positive result. To remedy all these defects and to obtain the tech-

nical results above set forth is the aim of this 50 invention.

In the accompanying drawings, Figure 1 is a longitudinal section on the line B B of Fig. 2. Fig. 2 is a plan view of Fig. 1. Fig. 3 is the plan view of a detail. Fig. 4 is a view of 55 the teeth of a saw, and Fig. 5 is a plan view of the same.

In carrying my invention into practice I provide a drum *a*, formed of crossed saw-bands *a'*, arranged at suitable intervals *a''* 60 upon an axis *b* and fixed thereon by means of a boss *c'* and screw and nut *c*. The formation of the teeth is the characteristic feature of this drum *a*. These teeth are all obliquely sharpened and are made alternately straight and crossed toward the right, then crossed to the left in order to become straight again, and so on. The teeth are slantly sharpened from points and cutting edges, the latter following alternately two on 70 the same side. Two right-slant edges alternate likewise with two left-slant edges, and so on. The drum *a* is set in rotation by a pulley *q* and is driven at a comparatively high speed. This disintegrating-drum *a* is 75 surrounded over a quarter of its periphery or thereabout with a casing *d*. The material supplied by the feeding-hopper *x* passes between the drum *a* and its casing *d* and is therein disintegrated or torn into fibers. For 80 this purpose the casing is provided with teeth on its inner periphery, Fig. 3, in which three recesses *e e e* alternate with four toothed surfaces. Two central surfaces *f f* are provided 85 with angular teeth, while the two remaining toothed surfaces *y* have parallel teeth, and this arrangement of alternate recesses and parallel and angular teeth has a very great importance on the technical effect to be obtained therefrom, the angular teeth *f f* serving to 90 push the glue pieces toward the center. This drum *a* may be brought more or less into close proximity to the casing *d* by means of screws *g* and hand-wheels *h*, and when the diameter of the saw-bands becomes smaller by wear 95 the casing *d* can be moved forward by a pressure-screw *i*, this casing being movable upon the axis *k*.

The upper part of the casing has the form of a pocket *l*, the peculiar form of which is of importance on the result sought for. In this pocket turns a fluted roller *m*, which is arranged in such a manner that between the same and the pocket is formed a gap or cleft, becoming narrower toward the drum *a*. This fluted roller *m* has for its object to convey over into the pocket *l* and away from the drum *a* the glue pieces supplied by the feeding-hopper *x*, whether it be thick or thin, so that it may be firmly held at one end in the narrowest part of the rift, where the fluted roller *m* and the pocket *l* come into contact, while the front part is already subject to treatment by the teeth of the disintegrating-drum *a*. The axis *n* of the fluted rollers *m* is movable and is pressed by weights placed on levers *r* against the pocket *l*. This pressure can be released by a hand-wheel *s* and can be regulated by a ratchet-wheel *t* so as to be applied wherever required. Material of different size can pass between the fluted roller *m* and the pocket *l*. Motion is imparted by means of two pairs of bevel-wheels and by shafts *o* and *u*, driven by pulleys *v v*. The pocket receives the material from a grinding-roller *p* with a rough surface. This roller is adjustable vertically, is rotated by the fluted roller *m*, and has for its object to seize the glue pieces dropping from the feeding-hopper *x*, to distribute the same, and to convey them to the entrance to the said pocket *l*. At the same time this roller *p* presses the raw material against the fluted roller *m* and acts thus simultaneously as conveyer and distributor, while preventing stoppages at the entrance to the pocket resulting from an undue pressure of the raw material against the fluted roller.

This machine operates as follows: The glue pieces are thrown as regularly as possible into the feeding-hopper *x*, whence they reach the grinding-roller *p*, which distributes them uniformly and conveys them to the entrance of the pocket *l*, where they are seized by the fluted roller *m* and passed on to the disintegrating-drum *a*. The teeth from the latter tear off fibers from the glue pieces while the same are firmly held by the fluted roller *m*. The shape of the teeth causes the pointed parts thereof to enter first the pieces of the skin, while the lateral edges cut off the fibers. The

pieces remaining after this treatment are further operated upon in the space between the drum *a* and its casing *d*, the teeth of the casing holding the pieces while the saw-teeth carry on their tearing action; but if the teeth were uniform over the whole of the inner periphery of the casing the glue pieces would be forced through the saw-teeth and pass untouched through the drum. It is for this reason that the recesses have been designed, in which recesses the pieces are thrown or slung through by reason of the great power developed by the centrifugal force. The angular-formed teeth of the central part of the casing guide and collect the glue pieces toward the axis of the machine.

As my improvements are capable of some modification without departing from the principle thereof, I do not restrict myself to the precise form and placement of the several parts thereof.

Having now described my invention, what I claim, and desire to secure by Letters Patent, is—

1. In a machine for disintegrating glue pieces for the manufacture of size, the combination of an adjustable curved casing, with a yieldingly-supported fluted roller, and a conveying and distributing roller, substantially as described.

2. In a machine for disintegrating glue pieces for the manufacture of size, the combination of an adjustable curved casing the upper part of which has the form of a pocket, with a yieldingly-supported fluted roller turning in said pocket, and a conveying and distributing roller with a rough surface, substantially as specified.

3. In a machine for disintegrating glue pieces for the manufacture of size, the combination of an adjustable drum formed of crossed saw-bands, with an adjustable curved casing provided with alternated recesses and parallel and angular teeth, and a fluted roller connected with an adjustable weight-lever, substantially as set forth.

In witness whereof I have hereunto signed my name in the presence of two subscribing witnesses.

CARL FRIEDRICH WURMBACH.
